UNITED STATES PATENT OFFICE.

HARRISON TAYLOR CRONK, OF NEW YORK, N. Y.

DESIGN FOR A CLOSET-BOWL.

43,269.

Specification for Design.

Patented Nov. 26, 1912.

Application filed August 2, 1912. Serial No. 713,010. Term of patent 14 years.

To all whom it may concern:

Be it known that I, HARRISON TAYLOR CRONK, a citizen of the United States, and a resident of the city of New York, borough of Manhattan, in the county and State of New York, have invented a new, original, and ornamental Design for Closet-Bowls.

Reference is to be had to the accompanying drawing, in which—

I claim—

The ornamental design for a closet bowl as shown.

HARRISON TAYLOR CRONK.
